UNITED STATES PATENT OFFICE.

ELMER E. NEAL, OF SPRINGFIELD, MASSACHUSETTS, ASSIGNOR TO HARCOURT BULL, OF SPRINGFIELD, MASSACHUSETTS.

CARTRIDGE-HOLDER.

No. 923,068

Specification of Letters Patent. Patented May 25, 1909.

Application filed April 9, 1908, Serial No. 425,980. Renewed February 26, 1909. Serial No. 480,159.

To all whom it may concern:

Be it known that I, ELMER E. NEAL, a citizen of the United States, residing at Springfield, Massachusetts, have invented certain new and useful Improvements in Cartridge-Holders, of which the following is a clear, full, and exact description:

My invention relates to cartridge holders and is adapted to support a number of cartridge shells for the purpose of being simultaneously inserted in and ejected from the chambers of a fire arm cylinder. In the present embodiment I have shown my device particularly adapted for use with grooved cartridge shells such as described and shown in my previous patent No. 881,437, dated March 10, 1908, but my invention is not confined to such use and may readily be adapted for use with the ordinary rimmed shells.

I preferably make my device out of a single piece of spring metal having a number of recesses located around the central portion thereof, the side portions of which are so constructed as to receive and retain a cartridge shell in said recess without the necessity of further securing means. As the action of each recess portion is independent of the others in retaining a shell, it is evident that one or two empty shells may be removed and new ones inserted without disturbance to the others. Also if one of the prongs or side portions of a recess becomes broken through rough use, the device is still serviceable for supporting the remaining shells. The recess portions of my device are also made sufficiently thin compared with the width of the grooves of the cartridge shells to permit a slight play, whereby any distortion of the holder does not prevent an easy insertion of the shell into the cylinder chambers as described in my previous patent referred to.

My invention will be defined in the claims.

In the embodiment shown in the drawings, Figure 1 is an end elevation of my cartridge holder showing a few cartridges supported therein, the head of one of said cartridges being removed; Fig. 2 is a longitudinal section of a revolver cylinder showing the position of a holder thereon; Fig. 3 is a cylinder section showing the action of the extractor upon the holder in removing the same with the empty shells; Fig. 4 is a

similar section to Fig. 2 but showing a modified form of cartridge in combination with my holder; Figs. 5 and 6 are different forms of my holder; and Fig. 7 is a detached view of a modified form of cartridge shown in Fig. 4.

The preferred form of my cartridge holder consists of a flat spring metal member 1 having a central perforation 2 adapted to fit around the usual turning ratchet 3 of a revolver cylinder 4. The annular portion 5 of the holding member rests on that portion of the extractor head 10 which ordinarily engages the rims of the ordinary cartridge shell. Extending preferably outwardly from the annular portion 5 of the holding member are pairs of curved prongs 6 forming substantially semi-circular recesses 7. The neck portion 8 of said prongs may be made slightly narrower than the body portions thereof to permit said prongs to more readily yield at this point when forced apart.

The outer ends of each pair of prongs or side portions 6 of the recess form an entrance or mouth 9 slightly narrower than the seat portion of said recess, and this mouth is also smaller than the diameter of the bottom of the groove 11 in the cartridge shell. The seat portion of the recess is of sufficient size to retain the shell securely therein, but with a slight amount of play. It is therefore plain that the resilient side portion 6 springs slightly apart when the cartridge shell is entering the recess and returns to normal position when the shell has been inserted, thereby retaining it therein. Although I have shown in the present embodiment both of the prongs or side portions 6 of the recess as resilient, it is obvious that my object will be obtained without departing from the spirit of my invention, by making only one side portion of each recess in this manner, as shown in my modification Fig. 6 in which 2^a designates the central aperture, 5^a the annular portion, and 7^a the recess seat. In this form only one of the side portions of the recess, such as 17^a, is made resilient. Fig. 5 shows one of the preferred forms of my holder in which the side portions 16^a of the recess are made broader for the purpose of affording a more substantial support when resting against the face of the cylinder.

In using my device the loaded shells pre-

viously snapped into the recesses of the holder are supported so as to simultaneously be inserted into the chambers of a fire arm cylinder. In the form shown in Figs. 2 and 3 the annular portion of the holder is then positioned between the cylinder and the recoil plate of the arm and engaging the head of the extractor operates on the holder to eject all of the shells simultaneously from the cylinder chambers.

In Fig. 4 I have shown a cartridge with a projecting shoulder 16 adjacent its groove 17, which, in this instance, engages the head 14 of the extractor at 15. When used with this form of cartridge my holder may engage the extractor head indirectly through the projecting shoulder of the cartridge, or a shoulder may be provided on the extractor head as in Figs. 2 and 3, to engage the holder. The holder in this case supports the cartridges in the same manner as in the other forms, while the projecting shoulder of the cartridge enables the same also to be used independently of the holder.

25 What I claim is:—

1. The combination with a cartridge holder, of a cartridge shell, one of said members having two supporting portions located in different planes coacting with a portion of the other member held therebetween to form mutual supporting means, said cartridge holder consisting of a substantially flat plate provided with a number of recesses around the central portion thereof adapted to receive said cartridge shells, said recesses having side portions which form a narrow mouth and a slightly larger seat portion therefor whereby said cartridges are retained therein.
- 40 2. The combination with a cartridge holder, of a cartridge shell, one of said members having two supporting portions located in different planes coacting with a portion of the other member held therebetween to form mutual supporting means, said cartridge holder consisting of a substantially flat plate provided with a number of recesses around the central portion thereof

adapted to receive said cartridge shells, said recesses having side portions which form a narrow mouth and a slightly larger seat portion therefor, one at least of the said portions being resilient whereby the cartridges are retained therein.

3. A cartridge holder which consists of a substantially flat annular plate adapted to engage an extractor head of a fire arm cylinder between said cylinder and the recoil plate of said arm, said plate provided with recesses around its annular portion adapted to receive cartridge shells, said recesses having side portions which form a narrow mouth and a slightly larger seat portion therefor whereby said cartridges are retained therein.

4. A cartridge holder which consists of a substantially flat annular plate adapted to engage an extractor head of a fire arm cylinder between said cylinder and the recoil plate of said arm, said plate provided with recesses around its annular portion adapted to receive cartridge shells, said recesses having side portions which form a narrow mouth and a slightly larger seat portion therefor, one at least of the side portions being resilient whereby the cartridges are retained therein.

5. The combination with a cartridge holder, of a grooved cartridge shell, said holder consisting of a substantially flat plate provided with a number of recesses around the central portion thereof adapted to receive cartridge shells, said recesses having side portions which form a narrow mouth and a slightly larger seat portion therefor, one at least of the side portions being resilient whereby the cartridges are retained therein, said cartridge shell being provided with a projecting shoulder adjacent its groove.

Signed at Springfield Mass this 28th day of March 1908.

ELMER E. NEAL.
